United States Patent Office.

PETER LAWYER, OF RICHMONDVILLE, NEW YORK.

Letters Patent No. 63,062, dated March 19, 1867.

IMPROVEMENT IN CARPENTERS' GAUGES.

The Schedule referred to in these Letters Patent and making part of the same.

TO ALL WHOM IT MAY CONCERN:

Be it known that I, PETER LAWYER, of Richmondville, Schoharie county, and State of New York, have invented a new and improved Metallic Gauge-Head and Fastener; and I do hereby declare that the following is a full, clear, and exact description thereof, which will enable others skilled in the art to make and use the same, reference being had to the accompanying drawing, forming part of this specification, in which—

Figure 1 is a longitudinal section of my improved gauge-head and fastener taken through the line x x , fig. 2.

Figure 2 is a cross-section of the same taken through the line y y , fig. 1.

Similar letters of reference indicate like parts.

My invention has for its object to furnish an improved gauge-head, simple in construction, easily, quickly, and accurately adjusted, and which, when its face has been once made at right angles to the rod, will always remain so; and it consists, first, in the combination of the cam-lever, lever-spring, and plate with each other; and second, in the combination of the flanged and slotted metallic eye with the plate, lever-spring, and cam-lever, as hereinafter more fully described.

A is the gauge-rod, which is made in the ordinary manner, and may be made of wood or metal, as may be desired. B is the eye of the gauge-head, which is made long, as shown in fig. 1, and has a broad flange, b^1 , around three sides of its forward end, which forms the face of the gauge-head. The face of the flange b^1 is so made as to be exactly at right angles to the rod A. The fourth side of the eye B is slotted, and the edges of said slot are flanged, which said flanges project upward at the front and rear ends of the eye B, and form ears, b^2 and b^3 . C is a plate fitting into the hole through the eye B, between the rod A and the slotted side of the said eye, as shown in figs. 1 and 2. The ends of the plate C are slightly turned up or flanged, to prevent it from slipping out of place when the gauge-head is moved backward or forward along the rod A. To the rear ears b^3 is pivoted the lever-spring D, which is of such a length and size as to fit exactly into the slot formed in the eye B, as shown in figs. 1 and 2. To the forward ears, b^2 , is pivoted the cam-lever E, the cam e^1 of which, when the lever is in the position shown in fig. 1, presses down upon the lever-spring D, and forces the spring D and plate C against the rod A, securing the gauge-head firmly and immovably to the said rod. But when the cam-lever is raised into a vertical position, the gauge-head can be moved into and adjusted in any desired position, the said lever E being held in either position by the elasticity of the spring D.

I claim as new, and desire to secure by Letters Patent—

The combination of the cam-lever E, lever-spring D, plate C, flanged and slotted metallic eye B, substantially as described, for the purpose specified.

PETER LAWYER.
